(57) **CLAIM**

The ornamental design for a display screen or portion
thereof with a graphical user interface, as shown and
described.

DESCRIPTION

The FIGURE is a front view of a display screen or portion
thereof with a graphical user interface, showing our new
design.

The dotted and evenly-dashed broken lines, specifically, 24
circles of a 5-by-5 array of circles, a rectangular bottom
banner including an outermost broken line that illustrates a
boundary of a display screen or a portion thereof, and all
